UNITED STATES PATENT OFFICE.

LANSING ONDERDONK, OF NEW YORK, N. Y., ASSIGNOR TO THE UNION SPECIAL SEWING MACHINE COMPANY, OF CHICAGO, ILLINOIS, A CORPORATION OF ILLINOIS.

FEEDING MECHANISM FOR BLINDSTITCH-MACHINES.

1,042,258.

Specification of Letters Patent. Patented Oct. 22, 1912.

Application filed July 31, 1902. Serial No. 117,878.

To all whom it may concern:

Be it known that I, LANSING ONDERDONK, a citizen of the United States, residing at New York city, in the county of New York, State of New York, have invented certain new and useful Improvements in Feeding Mechanism for Blindstitch - Machines, of which the following is a description, reference being had to the accompanying drawings and to the letters and figures of reference marked thereon.

My invention relates to an improvement in sewing machines, and more particularly to a feeding mechanism for a blind stitch sewing machine of the type illustrated in my prior Patent No. 721,077, granted February 17th, 1903.

The invention, therefore, consists in the matters hereinafter described and referred to in the appended claims.

The invention is illustrated in the accompanying drawings in which—

Figure 1 is a front elevation of a blind stitch machine embodying my invention, this figure representing the preferred form of the machine to which my feed mechanism is applied. Fig. 2 is a rear sectional end view of a portion of a machine embodying my invention. Fig. 3 is a sectional side view, broken away, through the center of the work support: Fig. 4 is a plan view, partly in section, illustrating the feed operating mechanism: Fig. 5 is a detail perspective view of the feed dog and its immediate operating parts: Fig. 6 is a detail view of the feed adjusting mechanism: Fig. 7 is a perspective view of the top feed mechanism, detached: Fig. 8 is a vertical section taken through the forward end of Fig. 7: Fig. 9 is a sectional side detail view of the top feed tripping mechanism.

Referring to the drawings, the machine shown is of the character indicated, and it is not necessary to refer specifically to the needle and looper operating mechanisms, nor to the work support C, except to state that the latter is cylindrical and is arranged to swing upon the standard A by means of the rock-shaft D², and is operated by hand lever E', as shown for example in Patents 721,077 and 721,079 granted to me Feb. 17, 1903. This hinging of the work support is to allow of the ready insertion and removal of the work.

B is the goose-neck, N the pitman connec-

tion from the driving shaft Q, for operating the support G, carrying the needle F, which needle in its movement is guided by the openings e, on the lower end of the arms a.

D is the throat plate and E the rib over 60 which the goods are crimped.

As above intimated, the feeding mechanism of the machine of the type referred to, includes two coöperating feeding arrangements, one, a lower feed mechanism inclosed 65 within the cylindrical casing or body plate C and carrying feed dogs which have up and down and forward and backward movements; and the other, a top feed mechanism.

Referring first to the lower or main feeding mechanism, two eccentrics g, h, are secured on the main or driving shaft between its two bearing points, which eccentrics operate two upright connecting rods i, k, the lower end of connecting rod i being 70 secured by ball and socket connection to the horizontal lever l. This lever l is fixed at its outer end to a shaft m, journaled in bearings in lugs on the front of the machine standard and is provided at its forward end with a curved slotted cross-head into which is fitted the head of a bolt n. On the bolt n is a ball sleeve o held firmly in place by the nut and washer p, q. Around the ball sleeve o, is clamped one end of the connecting rod s, the opposite end of which has a ball and socket connection, with the crank sleeve t fixed to one end of the feed dog actuating shaft u, which extends through the cylindrical bed plate, having suitable bearing lugs therein, and at its forward end is secured to a head 48, having a longitudinal slot 49 in its lower end, through which passes 80 a pivot pin, 50, having a squared head 51, to the outer end of which pivot pin, is attached the lower end of the feed dog carrying bar 52, having feed dogs 53, which feed dog carrying bar 52 is pivotally attached to one end of the arm 54, fixed to the outer end of the shaft u' by which the vertical movements are 85 imparted to the feed dog, the bar 52, sliding up and down as the link 54 oscillates.

The eccentric connection i through the lever l, shaft m with slotted cross-head, bolt n, sleeve o connecting rod s and sleeve t form 100 a universally jointed arrangement of parts, from which a conveniently adjustable oscillating movement is imparted to the feed shaft u during the revolution of the eccentric g, secured to the driving shaft. It is 110

this oscillation of shaft u , which determines the length of stitch, the variation of oscillation of said shaft being effected by the adjustment of connecting rod s , through parts n, o, q , to and from the center of the transverse shaft m .

The lower end of connecting rod z , is secured by a ball and socket connection to the bell crank lever x . Said bell crank lever x is secured on the transverse shaft m' , journaled in bearings in lugs extending from the rear side of the machine standard, the lugs being represented at y, z . To the lower end of x is secured by ball and socket connection 15 the connecting rod s' . The other end of the connecting rod s' has a ball and socket connection with a crank sleeve w' , which is firmly secured to the feed shaft u' , through which connection oscillatory motion is imparted to the shaft u' from the driving shaft. The purpose of the adjustable connection between the bell crank lever x and the connecting rod s' is to increase or diminish at will the up and down movement 20 of the feed dog, which is particularly desirable in a machine of this kind, to meet the variations in thickness and nature of the material to be sewn. Also by the ball and socket connection of parts, it will be seen 25 that the cylindrical work support or body plate may be dropped or raised more or less without affecting the action of the shafts u, u' and therefore the feed dog and the connecting parts will not bind. Thus a universal connection is provided at one end of 30 the feed dog shaft, between it and its operating shaft.

The numerals 55 and 56 represent two feed dogs having teeth in their lower forward edges projecting, one, 55 , into the space between the presser feet of the machine, and the other extending alongside, one of said presser feet, which presser feet for the sake of clearness, are not shown. These 45 feed dogs 55 and 56 are fixedly sleeved at the front of the machine to a shaft 59 extending longitudinally of the work support, said shaft being journaled in the upper ends of arms $60, 60$, fixed at their lower ends 50 to the rock shaft 61 journaled in bearings in a lug 62 , secured to the work support. This rock shaft is provided with an arm 63 , in which, near its upper end, is fitted a bolt 64 , upon which is pivoted one end of a link 65 , which at its opposite end is pivoted on a bolt 66 , secured to the upper end of the arm 67 , which latter is clamped upon the shaft u .

It will be seen, therefore, that as the shaft u oscillates, the shaft 61 rocks, and swings the arms 60 bodily, thus moving the feed dogs 55 and 56 bodily back and forth. Near its inner end, the shaft 59 has loosely mounted upon it the downwardly projecting arm 68 , which, at its lower end is provided with

the stud 69 , upon which is pivoted one end of a curved link 70 , which, at its lower end is pivoted on the stud 71 , secured in the lower end of the lever or crank 72 loosely sleeved on the shaft u' . This lever or crank 72 , is normally pinned to the crank 73 fixed at its upper end to the shaft u' . This pinning together of the two cranks is accomplished by means of a spring catch 74 , pivoted to the crank 73 , and having a latch engaging the slot 75 in the crank 72 .

When the cranks 72 and 73 are pinned together, they move as one and the oscillations of the shaft u' cause the arm 68 to oscillate. A leaf spring 76 is secured in the split end of the shaft 59 and at its free end rests between projections on the arm 68 . The swinging of the arm 68 will therefore, through the leaf spring 76 , cause the shaft 59 to oscillate and impart a yielding up and down movement to the feed dogs 55 and 56 . This yielding connection between the shaft 59 and its operating mechanism, allows the feed dogs to yield to varying thicknesses of material. When however, the spring catch 74 is released, the top feed dogs may be readily swung by hand up and down.

To provide for the automatic release of the top feed mechanism, when the work plate is lowered for the insertion or removal of the work, the spring catch 74 , has its lower end projecting downwardly into position to be engaged by a projection on the machine standard, whereby when the work support is lowered, the catch will be dropped, and release the crank 72 from engagement with the crank 73 , holding the catch in disengaged position, until the work support returns to elevated position, and the shaft u' begins to oscillate when the cranks 100 are again united.

The numeral 78 represents the curved arm or stop, movable with the feed to prevent relative movement of the body plate and head of the machine, when the needle is in the work, but this forms no part of the present invention.

The details of the top feed mechanism herein shown and described are not claimed, as they form the subject matter of patent of 115 April 18th, 1911, No. 990,160.

Various minor modifications and changes in the construction of the parts of this apparatus may be made without departing from the spirit of my invention.

Having thus described my invention, what I claim as new and desire to secure by Letters Patent, is:—

1. In a blind stitch sewing machine, having a suitable work support movable to allow insertion and removal of the work, needle and looper mechanism arranged and operating above the work support, a main feeding mechanism, arranged within the work support, and a top feed mechanism ar- 125 130

- ranged outside the work support, but having operative connection with the main feeding mechanism, whereby said top feed mechanism is operated in unison with the main feeding mechanism and means carried by said work support for supporting said top feed mechanism; substantially as described. 5
2. In a sewing machine, the combination with a work support, means for raising and lowering the work support, a main feeding mechanism located within the work support, a top feeding mechanism carried by the work support, and means whereby the top feeding mechanism may be moved from engagement with the fabric when the work support is lowered. 10
3. In a sewing machine, the combination with a work support, means for raising and lowering the work support, a main feeding mechanism contained within the work support, a top feeding mechanism carried by the work support, connections between the main feeding mechanism and top feeding mechanism, whereby the top feeding mechanism is operated in unison with the main feeding mechanism, and means whereby the top feeding mechanism may be moved out of engagement with the fabric when the work support is lowered. 20
- 30 4. In a sewing machine, the combination of a work support, means for raising and lowering said work support, a main feeding mechanism, a supplemental feeding mechanism, means for operating the supplemental feeding mechanism, and means for disconnecting the supplemental feeding mechanism from its operating means, operated by the lowering of the work support, substantially as described. 35
- 40 5. In a sewing machine, the combination with the main feeding mechanism, a work support, means for raising and lowering said work support, a top feeding mechanism including a plurality of feed dogs, means 45 for imparting a yielding up and down movement to said feed dogs, whereby said feed dogs may yield to varied thicknesses of material, and means whereby the top feeding mechanism may be lifted from the fabric 50 when the work support is lowered. 55
6. In a sewing machine having a work support, means for raising and lowering the same, a feed dog, an oscillating shaft for transmitting an oscillatory movement there- 60 to, means for oscillating said shaft, comprising a driving shaft arranged transversely of said oscillating shaft, an eccentric on said driving shaft, an eccentric connecting rod, a lever attached to the connecting rod, and a rock shaft to which the opposite end of said lever is attached, and connections between said rock shaft and the feed dog shaft, and means for adjusting said connections. 65
7. In a sewing machine having a work support, means for raising and lowering the 65
- same, a feed dog, an oscillating shaft for transmitting an oscillating movement thereto, means for oscillating said shaft, comprising a driving shaft, arranged transversely of said oscillating shaft, an eccentric on said driving shaft, an eccentric connecting rod, a lever attached to the connecting rod, a rock shaft to which the opposite end of said lever is attached, and connections between said shaft and the feed dog shaft, said connections including a universal connection at one end of the feed dog shaft. 70
8. In a sewing machine having a work support, means for raising and lowering the same, a feed dog, an oscillating shaft for transmitting an oscillatory movement thereto, means for oscillating said shaft, comprising a driving shaft arranged transversely of said oscillating shaft, an eccentric on said driving shaft, an eccentric connecting rod, a lever attached to the connecting rod, a rock shaft to which the opposite end of said lever is attached, and connections between said rock shaft and the feed dog shaft, said connections having a universal connection at one end to said rock shaft, and at the opposite end having a crank connection with the feed dog shaft. 75
9. In a sewing machine having a work support, means for raising and lowering the same, a feed dog, an oscillating shaft for transmitting an oscillatory movement thereto, means for oscillating said shaft, comprising a driving shaft arranged transversely of said oscillating shaft, an eccentric on said driving shaft, an eccentric connecting rod, a lever attached to the connecting rod, a rock shaft to which the opposite end of said lever is attached, and connections between said rock shaft and the feed dog shaft, said connections including a member adjustably connected at one end to said rock shaft, and at its opposite end connected with the feed dog shaft. 85
10. In a sewing machine having a feed dog raising and lowering shaft, a feed dog supported thereby and means for oscillating said shaft, comprising a driving shaft arranged transversely of said oscillating shaft, an eccentric on said driving shaft, an eccentric connecting rod, a lever attached to the connecting rod, and a rock shaft to which the opposite end of said lever is attached, and connections between said rock shaft and the feed dog raising and lowering shaft, and means for moving said feed dog back and forth to feed the fabric. 90
11. In a sewing machine having a feed dog raising and lowering shaft, a feed dog supported thereby and means for oscillating said shaft, comprising a driving shaft arranged transversely of said oscillating shaft, an eccentric connecting rod, a lever attached to the connecting rod, and a rock shaft to which the opposite end of said lever is at- 105
- 120
- 125
- 130

tached, and connections between said rock shaft and the feed dog raising and lowering shaft, said connections including a member connected at one end to said rock shaft and at the other end to the feed dog raising and lowering shaft, and means for moving said feed dog back and forth to feed the fabric.

12. In a blind stitch sewing machine having a work support, an overhanging frame supporting a needle and looper mechanism above the outer end of the work support, said support being movable to allow the insertion and removal of the work, a main feeding mechanism including two oscillating shafts contained within said work support, and a top feed mechanism mounted exteriorly of said support, but operatively connected to said shafts within said support.

13. In a sewing machine having a work

support, an overhanging frame supporting a needle and looper mechanism above the outer end of the work support, said support being movable to allow the insertion and removal of the work, a driving shaft arranged transversely thereof, an oscillatory feed shaft within the work support, an eccentric connecting rod, a lever attached to the connecting rod, a rock shaft to which the opposite end of said lever is attached, and connections between the rock shaft and said feed shaft, whereby the latter is oscillated.

In testimony whereof I affix my signature in presence of two witnesses.
